UNITED STATES PATENT OFFICE.

FESTUS G. WOODLOCK, OF ST. LOUIS, MISSOURI.

STRAIN-INSULATOR.

1,069,051.

Specification of Letters Patent. Patented July 29, 1913.

Application filed September 23, 1912. Serial No. 721,780.

To all whom it may concern:

Be it known that I, FESTUS G. WOODLOCK, a citizen of the United States, and residing at St. Louis, in the State of Missouri, have invented certain new and useful Improvements in Strain-Insulators, of which the following is a specification.

This invention relates to insulators and more particularly to strain insulators of the turn-buckle type adapted to be used for supporting electrical conductors, for bracing masts, towers and poles supporting electrical conductors, or in other places where an insulator of the above type is required.

15 The objects of this invention are to construct a device of this character which will be compact, durable, and simple in construction, and which will be capable of withstanding high mechanical strains and also 20 the high electrical strains incident to the use of high voltages.

Further objects will appear from the detail description taken in connection with the accompanying drawing, in which:

25 Figure 1 is an elevation of an insulator embodying this invention, and Fig. 2 is a longitudinal section on the line 2—2 Fig. 1, parts being shown in elevation.

Referring to the accompanying drawing 30 10 designates a central body or shank of insulating material such as glass, porcelain or the like. This body or shank is corrugated or ribbed as shown at 11 in order to increase the surface or current creepage distances be- 35 tween the parts which are electrically sep- arated. Internally threaded sleeves 12 of brass or other suitable material are embed- ded in the ends of the body or shank, and these sleeves preferably taper or increase in 40 diameter toward their inner ends and are each provided at their inner end with a flange or projection 13. By means of this construction the sleeves will be firmly an- chored in the insulating body. Oppositely 45 threaded eye bolts 14 having eyes 15 are screwed into the threaded sleeves. A cen- tral hole extends transversely of the insulat- ing body, and this hole is lined with a sleeve 16 of brass or other suitable material which 50 is embedded in the body and is provided with a flange or projection 17 to anchor the sleeve in the body.

The insulating body can be molded in any suitable manner well known to those skilled 55 in the art so that the body will be molded around the sleeves 12 and 16 to embed these

sleeves therein so as to form a unitary structure.

The device as completed will form a turn- 60 buckle having a body or shank of insulating material and having threaded eye bolts en- gaging threaded bolt-receiving members em- bedded in the ends thereof, and these bolt- 65 receiving members are in turn firmly an- chored in the insulating body so that the de- vice will possess great mechanical strength. Its insulating value will also be high since the terminals are separated by the body of the insulating material in which they are 70 embedded.

The device can be adjusted to tighten or 75 loosen the wire or cable in which it is insert- ed by rotating the body or shank 10. This can be done by inserting a tool such as a rod or screw driver into the central hole so that a great leverage may be obtained. This cen- 80 tral hole is lined with a metallic sleeve so that abrasion of the brittle insulating ma- terial will be prevented, since the tool en- gages and transmits the force through the 85 sleeve 16 which is embedded in the insulat- ing body. The sleeve 16 is positioned be- 90 tween the ends of the sleeves 12 and is there- fore insulated from both of these sleeves and from the eye bolts and the wire in which the 95 device is inserted; the device may therefore be adjusted to tighten or loosen the wire without danger of shock even if one of the eye bolts is connected to a high tension wire.

It is obvious that various changes may be 95 made in the details of construction within the scope of the appended claims without de- parting from this invention, and it is there- fore to be understood that this invention is not to be limited to the specific construction 100 shown and described.

Having thus described the invention what is claimed is:

1. A strain insulator comprising a body of 100 insulating material, internally threaded sleeves embedded in the ends of said body, said sleeves tapering and increasing in ex- 105 ternal diameter from their outer ends toward the center of the body, and threaded bolts engaging said sleeves.

2. An insulating turn-buckle the body of 110 which is composed of insulating material, said body having means completely embed- ded therein adapted to be engaged by a tool or the like to turn said body.

3. A strain insulator comprising a body of 115 insulating material, internally threaded

bolt-receiving members completely embedded and anchored in the ends of said body, threaded bolts engaging said threaded members, and a tool engaging member completely embedded in said body intermediate said bolt receiving members.

4. A strain insulator comprising a body of insulating material, internally threaded sleeves embedded in the ends of said body, 10 threaded bolts engaging said sleeves, and a

sleeve embedded in said body and extending transversely thereof adapted to be engaged by a tool or the like to turn said body.

In testimony whereof I affix my signature in presence of two witnesses.

FESTUS G. WOODLOCK.
